AUTOMATIC FIRE EXTINGUISHING
APPARATUS

Ernst Hügel, Luckenwalde, Germany

Application June 18, 1936, Serial No. 86,008
In Germany December 11, 1933

6 Claims. (Cl. 169—29)

The present invention relates to an automatic fire extinguishing apparatus which has the advantage over known arrangements in that it effects the work of extinguishing without making use of a driving device or motor.

Hitherto, constructions are known which, after the release of a locking device, eject the extinguishing substance by means of a device driven electrically. Other fire extinguishing apparatus are known which effect the ejection of the extinguishing substance by means of mechanism actuated by a spring or weight. The apparatus actuated electrically has the drawback that it must be equipped with special leads, for the current supply. These leads, however, are subjected to the destructive action of the fire, whereby the apparatus is obviously rendered useless. The extinguishing apparatus driven by weights or springs have the disadvantage that they complete their discharge in a short time, whereby the apparatus is rendered considerably less effective.

The device of this invention eliminates the aforementioned disadvantages in a simple manner in that it provides a spindle-driving device actuated by a weight which driving device releases or causes the ejection of the extinguishing substance which is situated at the lower end of the container. The ejection of the extinguishing substance sets a distributing screw *c* in operation. The subsequent distribution is automatically effected by the ejected extinguishing substance itself in that it trickles downwardly on to the distributing screw in such a manner that the latter is kept rotating.

The accompanying drawing illustrates diagrammatically a constructional form of this arrangement, wherein:—

Fig. 1 shows a side elevation of the fire extinguisher.

Fig. 2 shows a plan view of same.

Fig. 3 shows a side elevation partly in section.

Fig. 4 shows an enlarged vertical longitudinal section through the bottom portion of the apparatus, and

Fig. 5 shows a detail to an enlarged scale.

According to the accompanying drawing the fire extinguisher consists of a suitably torpedo-shaped container *a*, the top of which is provided with a device *b* by which the apparatus can be suspended and at the bottom end of which is situated the distributor means *c*. A filling opening is provided in the top and closed by a cover *d*. In the interior of the container *a* is arranged a driving spindle *e* having a steep or quick screw thread and on which is loosely mounted a weight

f formed internally with a screw thread. On the side of the weight *f* is provided a fin *f'* which engages in a groove *g'* provided in a tube *g* which surrounds the spindle *e* (Figs. 4 and 5). The groove *g'* extends substantially the length of the tube *g* and provides means to prevent the weight *f* from turning about its axis on the one hand, and on the other hand to effect the rotation of the spindle *e*, after the latter has been released, similarly to the well known manner of the driving nut of a drilling machine.

The spindle *e* is separated from the extinguishing substance by the tube *g*, and is supported like a bearing in the closed top thereof, so that it can rotate freely about its longitudinal axis whenever desired. The unthreaded bottom portion of the spindle *e* is perfectly smooth (Fig. 4) so that, when the weight *f* reaches its lowermost position (Fig. 4), the spindle can subsequently rotate freely if caused to do so. The weight *f* is secured in its lowermost position by means of an abutment support *h* secured to the inside of the protector tube *g*. The bottom end of the tube *g* is provided with holes *i* through which the extinguishing substance passes to the bottom opening *j* of the container *a*. When the extinguisher is in a position ready for use the opening *j* of the container *a* is kept closed by means of a fusible disc *k* forced against the edge of the bottom opening of the container *a* by means of a sharp conically shaped nut *l*. The nut *l* is mounted on a special screw thread *l'* provided on the smooth end of the spindle and is screwed tightly against the disc *k* so as to jam the same against the bottom of the container and support *h* to lock the spindle *e* against rotation.

The fire extinguisher is actuated in the following manner:—

In the ready for use position (Figs. 3, 4 and 5) the weight *f* is situated at the upper end of the spindle *e*. When the room in which the fire extinguisher is located, becomes excessively hot, the disc *k* melts and thus releases the spindle *e* for rotation. The weight *f* by gravity slides downwards as soon as the disc *k* melts (arrow Fig. 5) and in this way causes the rotation of the spindle *e* while at the same time the extinguishing substance which is now free to discharge is discharged through the openings *i* and *j* over the conical nut *l* onto the distributor *c* and is dispersed by the latter. Weight *f* cannot slide downward until the spindle *e* is released for rotation. When the weight *f* reaches its lowermost position, the distributor is still kept rotating by the impact thereon of the subsequent discharging extin-

guishing substance until the supply of the latter is exhausted.

I claim:

1. An automatic fire extinguisher comprising a casing for holding fire extinguishing material, said casing being formed to provide a discharge opening in the bottom thereof, a threaded spindle having one end rotatably mounted in an upper portion of said casing, the other end of said spindle extending outwardly of said casing through said discharge opening thereof, a portion of said spindle within said casing and adjacent the opening thereof being unthreaded, extinguishing material spreading means mounted on the extended end of said spindle and rotatable therewith, fusible means sealing said opening and surrounding said extended end of said spindle to lock the same against rotation, non-rotatable weighted means normally carried within said casing adjacent the top thereof, said weighted means being engageable with the threads of said spindle and being adapted to descend through said casing in engagement with the spindle thread when said fusible means is fused whereby to rotate said spindle and said material spreading means, said weighted means finally seating in said casing in engagement with said unthreaded portion of said spindle, said spindle being adapted to be rotated thereafter by the impact of said extinguishing material upon said material spreading means.
2. The structure of claim 1, and a tube within said casing surrounding said spindle, openings

in the lower end of said tube to permit the passage of extinguishing material therethrough, a portion of the inner wall of said tube being formed to provide means for guiding said weighted means in its descent.

3. In an automatic fire extinguisher including a casing having a bottom opening, a rotatable member below said opening for contacting and distributing extinguishing material descending through said opening, means operatively connected to said member for positively commencing the rotation of said rotatable member, and said rotatable member including means whereby the impact of said extinguishing material upon said rotatable member causes the same to continue to rotate as long as extinguishing material descends through said opening and contacts said rotatable member.

4. The structure of claim 1, and a member carried by the extended end of said spindle and cooperating with said fusible means to maintain the same in place to lock said spindle against rotation.

5. The structure of claim 3, fusible means sealing said opening and locking said rotatable member against rotation until said means is fused.

6. The structure of claim 3, fusible means sealing said opening and locking said rotatable member against rotation until said means is fused, and said means for commencing the rotation of said rotatable member comprising a weight.

ERNST HÜGEL.
